UNITED STATES PATENT OFFICE.

JOHN F. McDANIEL, OF LETART, WEST VIRGINIA.

SINGLE-TREE.

SPECIFICATION forming part of Letters Patent No. 279,410, dated June 12, 1883.

Application filed March 12, 1883. (No model.)

To all whom it may concern:

Be it known that I, JOHN F. McDANIEL, of Letart, in the county of Mason and State of West Virginia, have invented a new and Improved Single-Tree, of which the following is a full, clear, and exact description.

My invention consists of a single-tree for single or double vehicles, provided with swinging or opening trace-hooks, whereby the traces 10 may be quickly detached from the single-tree for detaching the horse or horses from the vehicle, and is more especially intended as a safeguard against breakage of the vehicle and injury to its occupants in case the horse or 15 horses become unmanageable.

The invention also consists of a detachable tongue-clip for the tongues of double vehicles, and of a spring attachment for the holdbacks of the thills of single vehicles, whereby complete detachment of the horse or horses from the vehicle will be effected upon the detachment 20 of the traces from the trace-hooks.

Reference is to be had to the accompanying drawings, forming part of this specification, in 25 which similar letters of reference indicate corresponding parts in all the figures.

Figure 1 is a perspective view of my new and improved single-tree arranged for holding the traces. Fig. 2 is a perspective view illustrating the method of detaching the traces. 30 Figs. 3 and 4 show, respectively, the thill and tongue holdback attachment to be used with my new and improved single-tree.

A represents the wooden portion of my new 35 and improved single-tree, upon the ends of which are fitted the metallic ferrules a. These ferrules are notched, as shown at b, and have pivoted upon them the steel plates c, which are formed or provided with the trace-hooks d, and with the downwardly-projecting lips e, 40 that are adapted to fit in the notches b of the ferrules a for holding the plates c in line with the length of the single-tree for holding the traces f on the trace-hooks, as shown in Fig. 1.

Rising from the spring-plates c are the arms 45 g, to which the ends of the strap h are attached. To the center of the length of this strap h is attached the strap h', which leads to the foot-brace, or other convenient parts of 50 the body of the vehicle in easy reach of the driver or other occupant of the carriage, so that by drawing upon this strap h' the outer

ends of the plates c will be simultaneously drawn upward, which upward movement will lift the projections e out of the slots b, and 55 thus permit the plates c to swing forward to the position shown in Fig. 2, and thus release the traces f.

i i are stop-plates attached to the single-tree for preventing the outer ends of the spring- 60 plates c being drawn upward too far.

In front of the holdback-iron j of the thills J, I attach the springs k, which reach up and bear at their outer ends upon the under side of the thills, which springs serve to retain the 65 holdback-straps when the traces are attached to the trace-hooks, but which will permit the holdback-straps to slip off from the thills when the traces are released; and to the tongue K, I attach the two springs l for holding the neck-yoke m, as shown in Fig. 4, which springs will 70 permit the passage of the neck-yoke between them when the traces are detached, thus admitting of the complete detachment of the team from the vehicle when the traces are released. 75

Constructed in this manner, it will be seen that the horse or horses may be quickly detached from the vehicle, and in case the horse or horses become unmanageable the device 80 furnishes a perfect safeguard against runaway accidents. Besides, the device is cheap and practical.

Other means whereby the holdback-straps and neck-yoke may be detached from the thills 85 or tongue might be devised and not depart from the spirit of my invention; and, instead of the notches b for holding the plates c back in line with the single-tree, pins, projections, or other means might be devised, and still involve 90 the spirit of my invention.

Having thus fully described my invention, I claim as new and desire to secure by Letters Patent—

The combination, with a whiffletree, of the 95 metallic ferrules a a, having end notches, b, and the end pivoted springs, c, having hooks d and lips e, whereby the trace-holders may be swung inwardly to release the traces, as described.

JOHN F. McDANIEL.
